UNITED STATES PATENT OFFICE.

NATHAN D. PHINNEY, OF NEW BEDFORD, MASSACHUSETTS.

GOODS-RACK.

SPECIFICATION forming part of Letters Patent No. 397,750, dated February 12, 1889.

Application filed November 13, 1888. Serial No. 290,757. (No model.)

To all whom it may concern:

Be it known that I, NATHAN D. PHINNEY, a citizen of the United States, residing at New Bedford, in the county of Bristol and 5 State of Massachusetts, have invented a new and useful Improvement in Goods-Racks, of which the following is a specification.

My invention relates to that class of devices which are designed to display such 10 goods as neckties, gloves, &c.; and its object is to provide a neat and handy device in which such goods can be displayed, and also be adjustable to the varying widths and sizes of such goods.

15 To this end my invention consists in a base of suitable length and width to the upper surface of which are attached in an adjustable manner suitable uprights for holding the goods in position on said base.

20 The accompanying drawing is a view in perspective of my invention.

In the accompanying drawing, *a* represents a base of suitable length and width, according to the kind of goods which it is designed 25 to carry, to which base are attached by means

of a screw, *c*, the slotted pieces *b b*. To the outer ends of the slotted pieces *b b* are fixed the uprights *d d*. By loosening the screw *c* it is obvious that the uprights *d d* may be adjusted to or from each other by means of the 30 slots *g* and secured there by tightening the screw *c*.

The uprights *d d* are of a length sufficient to support the quantity of goods which it is desired to display.

Having thus described my invention, what I claim is—

35 A goods-rack consisting of suitable uprights attached to slotted arms, which arms are secured to a suitable base by a screw passing 40 through the slots in the arms and into the base in such a manner that the uprights may be adjusted to or from each other by means of the slots in said arms, as may be desired, in order to support the goods to be displayed, as 45 shown and described.

NATHAN D. PHINNEY.
